(57) **CLAIM**

The ornamental design for a swimsuit, as shown and described.

DESCRIPTION

FIG. 1 is a front view of a swimsuit showing my new design according to a first embodiment of the present invention.

FIG. 2 is a rear view thereof.

FIG. 3 is a left side view thereof.

FIG. 4 is a right side view thereof.

FIG. 5 is a front view of a swimsuit showing my new design according to a second embodiment of the present invention.

FIG. 6 is a rear view thereof.

FIG. 7 is a left side view thereof; and,

FIG. 8 is a right side view thereof.

The broken lines illustrating a model are for environmental purposes only and form no part of the claimed design. The broken lines illustrating portions of the swimsuit form no part of the claimed design. The dot-dash broken lines define the bounds of the claimed design and form no part thereof. The portions of the swimsuit that include grayscale compared to the portions of the swimsuit that do not include grayscale represent a contrast in appearance.
